UNITED STATES PATENT OFFICE.

HENRY S. DIX, OF CHELSEA, MASSACHUSETTS, ASSIGNOR TO SYLVESTER B. HINCKLEY, OF SAME PLACE.

MACHINE FOR CUTTING LATH-YARNS.

SPECIFICATION forming part of Letters Patent No. 482,917, dated September 20, 1892.

Application filed February 24, 1891. Serial No. 382,430. (No model.)

To all whom it may concern:

Be it known that I, HENRY S. DIX, of Chelsea, in the county of Suffolk and State of Massachusetts, have invented a new and useful Improvement in Machines for Cutting Lath-Yarns, which will, in connection with the accompanying drawings, be hereinafter fully described, and specifically defined in the appended claims.

10 In said drawings, Figure 1 is a perspective view taken at a point at the right and rear of the machine. Fig. 2 is a front elevation of the machine, the vertical supports that bear upon the floor and the right-hand portion of 15 the machine being in part broken away. Fig. 3 is a rear elevation of the principal portion of the machine that is shown in Fig. 2. Fig. 4 is an end elevation taken at the right in Figs. 1 and 3 and at the left in Fig. 2 and with 20 the feeding device removed. Fig. 5 is a view like Fig. 4, but with the feeding device in place. Fig. 6 is a detached view to be explained. Fig. 7 is a sectional elevation showing the crank-shaft, the pulley thereon, the 25 coating-clutch, the clutch-key, and the retractile spring of said key. Fig. 8 is a side elevation showing the crank-shaft, pulley, clutch, clutch-key, armature, helix, and retractile spring. Fig. 9 is an elevation showing the 30 crank-shaft and the interior of the pulley which is engaged by the clutch. Fig. 10 is an elevation of the clutch-spline.

The object of my invention is to provide a machine that will with certainty and desired 35 rapidity cut into intended lengths or sections a series of "lath-yarns," so called, such yarns being first laid together to form a long cylindrical body termed a "junk;" and the invention consists in certain novel features and the 40 combinations thereof, as will be hereinafter described, and pointed out in the claims.

Referring again to said drawings, A represents a main pillar resting upon the floor and supporting the head or main portions of the 45 machine, while B, B', B'', and B''' are supports of various parts of the machine to be described. A head C, having a passage through it, as shown in Figs. 1, 2, and 3, is secured upon pillar A and has journaled in it near 50 its top a crank-shaft a , on which is mounted a loose pulley b , which has secured to it a

clutch c , which carries a spline 40 , arranged to engage with and be disengaged from said pulley. Said clutch interlocks the pulley b with shaft a by means of spline 40 , said spline 55 being disconnected from the pulley by the rising of the inner end of the key or lever d when it is released from the electro-magnets 14, to the pole of which its outer end is drawn at the proper moment by its contact-plate 29, 60 and at the proper moment when the outer end of said lever is raised to contact with the poles of the magnets the spring 41 instantly forces spline 40 into its seat in pulley b , which seats are shown in Fig. 9, the inner end of 65 said key d being beveled to an edge, so as to enter between said spline and the end face of the clutch. A pitman f , formed at its lower end as a cross-head that moves upon ways on head C, is secured upon the wrist-pin of the 70 crank of shaft a , (see Fig. 2,) and in the lower portion of said pitman is secured a bar g , to which is secured the cutter h , the edge of which extends across the end face of tube or sleeve i , through which the junk that is being cut moves. In brackets n , secured to the base of said head C, are journaled the short shafts j , upon which are secured the enmeshing gears k , Fig. 5, motion being imparted thereto by a belt acting upon pulley 75 l , secured upon the lower shaft. Upon said shafts, respectively, are secured the groove-faced rolls m , the circular opening between the same being exactly in line with the passage through sleeve i , so that as the junk 80 is fed forward by the conjoint action of the rolls it passes onward through said sleeve till severed by knife h , as will be again referred to. Upon the lower shaft j is secured the pulley p , which drives belt t , that at its opposite end engages and drives pulley v on shaft w . (See Fig. 1.) A pulley on said shaft 85 w drives the carrier-belt x , which at its opposite end passes around a pair of "idle." (See Figs. 1 and 2.) A bed y is arranged beneath 90 the upper portion of belt x to support the junk, which by the action of the belt conjointly with rolls m is carried forward upon the belt in a right line till severed by the knife, as already stated.

100 A clearer-shaft z is pivotally supported in the top portion of the machine, as shown, and

is provided with a series of depending fingers 2, which extend close to but not touching belt α . When said shaft is at rest, the fingers are in the rear of belt α , so that when vibrated 5 toward the front they will sweep the severed section of junk in that direction and upon the delivery-apron, to be described. Said shaft is rocked by means of its rigid arm 3, to which is pivoted connector 4, that is at its 10 lower end pivoted to the reciprocating bar 5, that is supported and slides in studs secured in head C, as shown, said bar carrying in its upper forked end a cam-roll 6, that engages cam 7, secured upon crank-shaft α . (See Fig. 15 2.) Said cam is so formed and positioned upon shaft α and relatively to roll 6 that the shaft and cam can rotate a limited distance before bar 5 is started downward, thereby insuring the severing of the junk by knife h 20 before fingers 2 are moved into contact therewith.

When the crank of shaft α rises, it thereby allows bar 5 to rise, such action being effected by the retracting-spring 8, supported from 25 above the machine and attached to arm 3, thereby not only holding the roll in contact with the cam, but also swinging fingers 2 to their rearmost position in readiness to repeat the operation.

30 Upon shaft w , at the end opposite pulley v , is secured the bevel-gear 9, which enmeshes with a similar gear 10, secured upon the roll-shaft 11, which drives the endless apron 12, which at its outer or front extremity is supported by 35 a roll 13, and which carries to the packing-case the severed sections of junk as the same are swept upon the belt, as already specified.

To produce the intermitting rotation of crank-shaft α , and thereby the reciprocation 40 of cutter h , I employ the following-described devices: An electric conducting-wire 15, duly supplied with a current, is secured to screw-cap 17, mounted on the insulated metal plate 19, contact therewith is made by arm 20, secured on rock-shaft 18, supported in sleeve 28, secured, like plate 19, on a wooden block 25. Said wire 15 is secured by a cap-screw to said 45 shaft 18 and passes thence back to the electric generator, thus establishing a circuit. An 50 electro-magnet consisting of coils 14 14, connected together and duly supported, as shown, is by a wire 16 connected with wire 15 at a point before it reaches cap-screw 17 and at a point after it leaves the cap-screw in shaft 18.

55 Auxiliary contact between said shaft 18 and sleeve 28 is had by means of angle-plate 31, secured upon a wooden block 25 and resting upon the sleeve 28, a short wire being extended from the shaft to said plate, as shown.

60 To break the contact between arm 20 and plate 19, a rod 21 is secured in a standard secured upon block 25, as shown, and upon the front end of said rod is pivotally suspended the arm 22, upon which is pivoted the catch 65 23, which engages arm 24, secured upon shaft 18, as shown. The lower and broadened end of arm 22 is in such close proximity to the

upper side of the junk-carrying belt α that as the junk moves forward it engages the arm and takes it along with itself and, through 70 catch 23, arm 24, and shaft 18, breaks the electric circuit by raising arm 20, secured on said shaft, from off the plate 19. When the direct circuit is thus broken, the current will pass by said wire 16 through the electro-magnet, when armature 29, secured on lever d , will be raised into contact with the poles of said magnet, thereby through lever d withdrawing the spline and allowing the clutch to interlock with pulley b , and thereby rotate 75 shaft α , as specified, and through the means already described severing the junk and sweeping the section thus cut from belt α onto the carrier-apron 12, allowing the circuit-shifting devices to resume their former 80 position automatically, thus removing the circuit from the electro-magnet, whereupon the armature falls, aided by spring e , in readiness to repeat the operation. When the outer end of key d is raised by the magnets and the 85 spline 40 has been thereby allowed to engage pulley b , it will so continue for one revolution and no more, as the electric trip 23 on arm 22 will have momentarily sent the current through magnets 14 to liberate spline 40, 90 which will be retracted by key d when it again reaches its lowest point, where the clutch stands when at rest, as it is exactly opposite the crank, and so as to allow the free 95 passage of the junk past the cutter, except at the instant of severing it, so that the cutter shall not interfere with the passage of the junk through the guiding-sleeve.

It will be obvious that by adjusting and locking block 25 upon bar 27 at any desired 105 point the sections of junk being severed may be of any length that the intended use may require. The sleeve i , against the end face of which the cutting-knife h acts in severing the junk, constitutes, in fact, one member of 110 a shear or cutting-die, and hence must be made of first-quality cast-steel and duly tempered for the performance of the work required of it.

I claim as my invention—

1. The combination of the junk-feeding mechanism, consisting of a pair of driven groove-faced rolls and a driven carrying-belt, a junk-severing cutter, with means to actuate the same, a clutch mechanism by which 120 the knife-actuating devices may be rendered operative and inoperative, an electro-magnet arranged to operate the clutch-engaging devices, and an electric circuit connected with said magnet to render the same operative and 125 provided with a circuit-breaker arranged to be actuated by contact therewith of the junk as it is advanced by the feeding device.

2. In a junk-cutting machine, the combination, with a feeding and severing mechanism, of the clearer, consisting of shaft z , having fingers 2, the arm 3, arranged on said shaft, the shaft α , arranged to be periodically rotated, and the cam 7, secured on said shaft α

and arranged to act upon and depress the roll 6, and thereby actuate shaft z, all substantially as specified.

3. The combination of the grooved feed-
5 rolls and junk-carrying belt, the crank-shaft
having the cutting - knife connected there-
with and provided with an interlocking clutch,
the electro - magnets, the armature thereof
and the clutch-engaging key, and the elec-

tric circuit embracing said magnets and pro- 10
vided with a circuit-breaker with the actu-
ator thereof arranged in the path of the junk
as moved forward by said feeding devices.
